UNITED STATES PATENT OFFICE

GEORGE SAKIER, OF NEW YORK, N. Y., ASSIGNOR TO STANDARD SANITARY MANUFACTURING COMPANY, OF PITTSBURGH, PENNSYLVANIA, A CORPORATION OF NEW JERSEY

DESIGN FOR A PEDESTAL FOR LAVATORY BASIN

Application filed February 2, 1931. Serial No. 38,529. Term of patent 14 years.

To all whom it may concern:

Be it known that I, GEORGE SAKIER, a citizen of the United States, residing at the city of New York, borough of Manhattan, in the county and State of New York, have invented a new, original, and ornamental Design for Pedestal for Lavatory Basin, of which the following is a specification, reference being had to the accompanying drawings forming a part thereof.

In the drawings—
Figure 1 is a front elevation of the article embodying my new design;
Fig. 2 is a side elevation, and
Fig. 3 is a plan or top view.

I claim:
The ornamental design for a pedestal for lavatory basin, as shown.

GEORGE SAKIER.
